UNITED STATES PATENT OFFICE.

ELMYR A. LAUGHLIN, OF CHICAGO, ILLINOIS.

SIDE BEARING.

1,131,252.

Specification of Letters Patent. Patented Mar. 9, 1915.

Application filed January 28, 1914. Serial No. 814,921.

To all whom it may concern:

Be it known that I, ELMYR A. LAUGHLIN, a citizen of the United States of America, and a resident of Chicago, county of Cook, 5 and State of Illinois, have invented certain new and useful Improvements in Side Bearings, of which the following is a specification.

The main objects of this invention are to 10 provide an improved form of side bearing wherein the support or housing for the roller is formed in one piece and the roller is provided with a removable trunnion shaft; to provide an improved location of 15 the openings in said support through which the trunnion shaft may be passed when being located in said roller; to provide improved means for preventing the removal of the trunnion shaft through said openings; and to provide an improved construction 20 of the trunnion guideways whereby the roller is normally urged toward a central position when free from the load and is prevented from being thrown toward the 25 ends of the guideways when the load is suddenly relieved therefrom at a time when the car is in motion.

An illustrative embodiment of this invention is shown in the accompanying drawings, in which—

Figure 1 is a side elevation of a roller bearing embodying the improvements above specified. Fig. 2 is a longitudinal sectional elevation of a roller bearing, the right half 35 of the view representing a slight modification in the formation of the trunnion guideways. Fig. 3 is a transverse sectional elevation of the bearing as shown in Fig. 1.

In the construction shown in the drawings, the support or housing 4 is formed of a single malleable casting in which a roller runway 5 and trunnion guideways 6 are formed. The support is provided with integral side flanges 7 by means of which the 45 support is secured to the body of the car, in the usual manner.

A roller 8 is mounted in the runway 5 and is adapted to have a limited range of travel therein. A removable trunnion shaft 9 is secured in the roller 8 with the trunnions or ends thereof located in the trunnion guideways 6. The roller 8 normally bears between a wear plate 11 carried by the support 4 and a wear surface or plate

12 carried on the truck bolster (not shown). 55 The wear plate 11 is inserted into place through slots 13 formed at the sides of the support below the flanges 7 and is secured against dislodgment by means of lugs 14 formed on the support 4 and adapted to be 60 bent up, into the position shown in Figs. 1 and 3, after the plate has been inserted.

The lower guide surfaces of the trunnion guideways 6 are provided with a plurality of shoulders stepped downwardly from the 65 ends of the guideways to the middle thereof. In the construction herein shown these shoulders are in the form of end ledges 15, and a substantially horizontal middle part or ledge 16, between which are formed a 70 plurality of other horizontal steps or ledges 17. The inner corners of the ledges 15 and 17 are located slightly outward of a transverse vertical plane passing through the axis of the roller when the trunnion 10 engages one of the corresponding ledges so that the center of gravity of the roller is inward of the respective shoulder corner whereby the roller normally tends to roll 75 toward a central position in the runway. 80 This construction of the lower guide surfaces for the trunnion is much more effective than a gradually inclined construction in preventing the roller from being thrown toward the ends of the runways when the 85

car is suddenly started or stopped in such a manner as to cause the load to be lifted from the roller. When a car has the brakes applied suddenly, the springs are compressed on the forward end of the truck and the 90 rear end of the truck is lifted due to the pulling and pushing action of the brakes. This results in a tilting of the truck bolster, which in turn elevates the rear edge of the center plate, tending to lift the car and free 95 the rollers in the side bearings from their loads. At the same time the forward end of the wear plate under the roller is depressed thereby tending to further free the roller. If the roller is not obstructed, or has simply 100 a small inclined guide surface, it will roll forward to the end of the runway, due to its own momentum, and the minute the car stops, or even if it does not stop and the brakes are released, the truck resumes a 105 normal position and is likely to catch and hold the roller at the end of its travel. However, under similar circumstances, with

a construction of the character herein shown, the roller would not have sufficient momentum to ascend from one to the other of the ledges, but would be retained on the 5 central ledge 16 ready to receive the load and resume its normal functions immediately upon the return to normal operating conditions. The upper guide surfaces 18 are inclined inwardly and upwardly so 10 that as the roller approaches either limit of its travel the load will be transferred from the periphery of the roller to the trunnions and the car slightly elevated with respect to the truck, as more fully described and 15 claimed in my co-pending application, Serial No. 748,956.

Circular openings 19, substantially equal in diameter to the diameter of the trunnion shaft 9, are formed in the sides of the frame 20 4 through which the trunnion shaft 9 may be passed for insertion into the roller 8 when said roller is located in the runway 5 with the axis thereof in alinement with the axis of said openings. These openings 25 are located with their axes substantially halfway between the positions which the axis of said trunnion shaft would occupy when the roller is either engaging the wear plate 11 and supporting the load, or when 30 the trunnions 10 are resting on the middle ledge 16. It would therefore be quite impossible for the roller to accidentally come into alinement with said openings in such a way as to permit the removal of the trunnion shaft. If the trunnion shaft 9 is to be 35 removed or inserted, it is necessary for the roller to be held in a position intermediate those positions which it normally occupies when carrying the load or when relieved 40 from the load.

A plurality of small apertures 20 are formed in the support 4 concentrically of the opening 19 so as to provide shoulders or abutments 21 adjacent to said openings 45 19 which may be forced inwardly, as shown in Fig. 1, so as to distort the openings 19 and prevent removal of the trunnion shaft 9. The shoulders 21 are readily forced inwardly by driving a drift key into the openings 50 20.

Although but one specific embodiment of this invention has been herein shown and described, it will be understood that numerous details of the construction shown 55 may be altered or omitted without departing from the spirit of this invention as defined by the following claims.

I claim:

1. A side bearing, comprising a support 60 having a roller runway formed therein, a roller mounted in said runway and adapted to have a limited range of travel therein, trunnions on said roller, said frame having guide surfaces adapted to support said trunnions when the load is relieved from said 65

roller, said guide surfaces being formed with a series of shoulders stepped successively downward from the ends of said guideways toward the middle thereof.

2. A side bearing, comprising a support 70 having a roller runway formed therein, a roller mounted in said runway and adapted to have a limited range of travel therein, trunnions on said roller, said frame having guide surfaces adapted to support said trunnions when the load is relieved from said 75 roller, said guide surfaces being formed with a series of shoulders stepped successively downward from the ends of said guideways toward the middle thereof, each of said shoulders being so located that when the trunnion of the roller is in contact therewith the center of gravity of the roller is inward of such shoulder whereby the roller will be caused to roll toward a middle 80 position in said runway.

3. A side bearing, comprising a support having a roller runway formed therein, a roller mounted in said runway and adapted to have a limited range of travel therein, 85 trunnions on said roller, said frame having lower horizontal guide surfaces adapted to support said trunnions when the load is relieved from said roller, and shoulders on said frame located adjacent to the ends of 90 said guide surfaces and spaced above the plane thereof, said shoulders being adapted to engage the trunnions of the roller when said roller is released from the load at the end of its travel and cause said roller to roll 95 by gravity toward a middle position in said runway.

4. A side bearing, comprising a support having a roller runway formed therein, a roller mounted in said runway and adapted 100 to have a limited range of travel therein, trunnions on said roller, said frame having guide surfaces adapted to support said trunnions when the load is relieved from said 105 roller, said guide surfaces being formed with substantially horizontal end ledges and a substantially horizontal middle ledge located at respectively different elevations. 110

5. A side bearing, comprising a support having a roller runway formed therein, a 115 roller mounted in said runway and adapted to have a limited range of travel therein, trunnions on said roller, said frame having guide surfaces adapted to support said trunnions when the load is relieved from said 120 roller, said guide surfaces being formed with a plurality of ledges located in successively lower positions from the ends to the middle part thereof.

6. A side bearing, comprising a support 125 having a roller runway formed therein, a roller mounted in said runway and adapted to have a limited range of travel therein, trunnions on said roller, said frame having guide 130 surfaces adapted to support said trunnions 135

when the load is relieved from said roller, said guide surfaces being formed to provide a ledge at each end thereof and a substantially horizontal middle part spaced below 5 the plane of said end ledges.

7. A side bearing, comprising a support having a roller runway formed therein, a roller mounted in said runway and adapted to have a limited range of travel therein, 10 trunnions on said roller, said frame having guide surfaces adapted to support said trunnions when the load is relieved from said roller, said guide surfaces being formed to provide a ledge at each end thereof and a 15 substantially horizontal middle part spaced below the plane of said end ledges, and a plurality of ledges formed at different elevations between said end and middle parts.

8. A side bearing, comprising a support 20 having a roller runway formed therein, a roller mounted in said runway and adapted to have a limited range of travel therein, trunnions on said roller, said frame having guide surfaces adapted to support said trunnions when the load is relieved from said roller, said guide surfaces being formed with 25 a plurality of ledges located in successively lower positions from the ends to the middle part thereof, the inner end of each of said 30 ledges being located outward from a vertical plane passing through the axis of said roller when the respective trunnion is engaged with such ledge.

9. A side bearing comprising a support 35 having a roller runway and trunnion guideways formed therein, a roller mounted in said runway and adapted to have a limited range of travel therein, trunnions on said roller extending into said trunnion guideways, said support having the upper surfaces of said trunnion guideways inclined 40 upwardly and inwardly and having the lower guide surfaces formed in a plurality of ledges located in successively lower po-

sitions from the ends of said guide surfaces 45 to the middle.

10. A side bearing, comprising a support having a roller runway and trunnion guideways formed therein, a roller mounted in said runway and adapted to have a limited 50 range of travel therein, said support having an opening in one side thereof leading into said trunnion guideways, a trunnion shaft adapted to be passed through said opening and into said roller when said roller 55 is placed in said runway with the axis thereof in alinement with said opening, said frame having an aperture located adjacent to said opening and adapted to have means inserted therein for forcing the metal of 60 said frame between said aperture and opening into said opening so as to prevent said trunnion shaft from being withdrawn from said roller.

11. A side bearing, comprising a support 65 having a roller runway and trunnion guideways formed therein, a roller mounted in said runway and adapted to have a limited range of travel therein, said support having a wear surface adapted to engage the roller 70 for supporting the load, said support also having an opening in one side located with the axis thereof between the positions which the axis of said trunnions would occupy, when the load is being carried by the roller 75 and when the trunnions are resting on said lower guide of said guideways, and a removable trunnion shaft adapted to be passed through said opening and into said roller when said roller is placed in said runway 80 with the axis thereof in alinement with the axis of said opening.

Signed at Chicago this 23d day of January 1914.
